UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

HANGER AND TRACK THEREFOR.

SPECIFICATION forming part of Letters Patent No. 753,481, dated March 1, 1904.

Application filed November 27, 1903. Serial No. 182,740. (No model.)

To all whom it may concern:

Be it known that I, HENRY L. FERRIS, a citizen of the United States of America, residing at Harvard, in the county of McHenry and State of Illinois, have invented certain new and useful Improvements in Hangers and Tracks Therefor, of which the following is a specification.

My invention relates to certain new and useful improvements in hangers and tracks therefor; and its object is to produce devices which shall have certain advantages, which will appear more fully and at large in the course of this specification.

15 My invention is illustrated in the accompanying drawings, in which—

Figure 1 is a section through my improved track, showing a hanger placed thereon, the hanger illustrated being the upper portion of 20 a hay-carrier; and Fig. 2 is a perspective view of a portion of my track.

Referring now to the drawings, it will be seen that the track consists of two similar portions A, which are riveted together by rivets 25 a. Each portion A consists of a vertical web a' , an inclined web a^2 , and a horizontal web which projects upon opposite sides of the inclined web a^2 , the portion projecting upon one side being indicated in the drawings by a^3 and that upon the opposite side by a^4 . The rivets a , it will be noticed, pass through the vertical portions a' . This track is supported by rods or bars, one of which is shown at B, each of these rods or bars being provided at 35 its lower end with an enlarged head B', which lies between the inclined webs a^2 and underneath the inwardly-projecting portions of the horizontal webs. The hangers which are used with this type of track are substantially

40 similar to the double-roller hangers heretofore in use, each consisting of a suitable frame C, which has upwardly-projecting portions C', to which are journaled pulleys C², which run upon the horizontal webs of the track. These 45 hangers preferably differ from the hangers heretofore in use in that each upwardly-projecting portion C' has an inwardly-projecting lug c, which lies underneath the outer half a^4

of the horizontal web and engages therewith if the hanger is tilted. This prevents the 50 hanger from falling off the track.

I realize that tracks have heretofore been made which were composed of two symmetrical pieces of metal riveted together and that these tracks also had horizontal webs below 55 which lay the head of the supporting rod or member, and I do not, therefore, claim such a device as my present invention. The addition, however, to such a track of the outwardly-projecting portion of the horizontal 60 web, combined with the lugs upon the hangers which co-operate therewith, is particularly desirable, for by this means it is made entirely impossible for the hanger to fall off the track under any circumstances. This device 65 is particularly desirable for use upon hay-carriers, where the load is likely to receive considerable lateral strain and may therefore upset the hanger.

A further advantage of this track consists 70 in the fact that the diagonal webs meet the horizontal webs substantially at their centers instead of at their outside edges, and consequently a lighter track can be made having the same width horizontal portions and the 75 same distance between said portions. In making a comparatively cheap track the difference in weight of material necessary to make this track and the tracks heretofore in use is very considerable, and consequently this track 80 can be put upon the market at a lower price.

I realize that considerable variation is possible in the details of this construction without departing from the spirit of the invention, and I therefore do not intend to limit 85 myself to the specific form herein shown and described.

I claim as new and desire to secure by Letters Patent—

1. The combination with a track having horizontal portions to form a double tread, separated by a practically continuous slot, of diagonally-disposed portions meeting said horizontal portions substantially at their centers, said diagonally-disposed portions being joined 95 at their lower edges, and a carrier having roll-

ers adapted to run on said horizontal portions.

2. The combination with a track having horizontal portions to form a double tread, separated by a practically-continuous slot, and portions connecting said horizontal portions to leave the outer edges of the same projecting laterally, of a carrier having rollers adapted to run upon said horizontal portions, and lugs secured to said carrier and projecting under the outwardly-extending edges of said horizontal portion.

3. The combination with a track, having horizontal portions forming a double tread, separated by a practically-continuous slot, of inclined webs extending downwardly from said horizontal portions, substantially at their center, to leave projecting edges on each side of each of said horizontal portions, means for supporting the track, engaging the inwardly-projecting edges of the horizontal portions, a carrier having rollers adapted to run upon said horizontal portions and having lugs extend-

ing underneath the outer edges of said horizontal portions.

4. The combination with a track composed of two symmetrical pieces, each consisting of a vertical web, a diagonal web, and a horizontal web, said horizontal web extending on both sides of the diagonal web, and the two halves of said track being riveted together by rivets passing through the vertical webs, of means engaging the inner edges of the horizontal webs for supporting the track, and a carrier having rollers running on the horizontal webs and having lugs extending underneath the outer edges thereof.

In witness whereof I have signed the above application for Letters Patent at Harvard, in the county of McHenry and State of Illinois, this 6th day of November, A. D. 1903.

HENRY L. FERRIS.
